WILLIAM SCHMITZ, OF NEW YORK, N. Y., ASSIGNOR TO S. & S. MACHINE & TOOL CO., A
PARTNERSHIP COMPOSED OF GEORGE SCHAAB AND WILLIAM SCHMITZ.

HEATING UNIT FOR PERMANENT HAIR WAVING.

Application filed May 21, 1925. Serial No. 31,896.

This invention relates to electrical heating units for permanent hair waving. Such heating units generally consist of a tubular casing equipped with a heating resistance 5 adapted to be applied to a previously prepared coil of hair of the head of the person to be treated. It has been found that these units, as now constructed, and which are to be suspended by means of its main leads and 10 a plug from an electric source provided immediately above the head treated, are objectionable because of the difficulty in handling the same, when in operation, as they become very hot. In fact, the heat, notwithstanding the insulation means used, is so great that not only can the unit not be touched by the operator but it is even strongly felt, when coming near the unit with the hand.

20 Another objection is that the heating units being directly suspended from the sockets in the ceiling by the leads, the latter, owing to the appreciable weight of a unit and the movements when handling them, have the 25 tendency to become loose and cause a short circuit, endangering the person treated or at least burning her hair.

The object of my invention is to provide simple means, whereby these objections can 30 be obviated.

My invention will be understood from the following detailed description by reference to the accompanying drawing in which similar references denote corresponding parts and 35 Fig. 1 is an elevation of a heating unit equipped with my new device; Fig. 2 a top plan view thereof and Fig. 3 a vertical section of the upper part of the unit and of my device.

40 *a* denotes the heating unit, which is of well-known construction, the same consisting of tubular heating sections *a'*, *a''* containing the electric heating resistances (not shown), which are directly connected to the 45 main leads *b* adapted to be connected by a plug (not shown) to a socket of the electric source generally arranged on the ceiling above the head of the person treated. These leads are, as usual, fastened to the terminal 50 screws *c* of the electrical resistances, which screws are provided in the cylindrical head-piece fixed to the top of the upper section *a'* and made of bakelite or other insulating material.

55 In handling this unit, the insulated head

at the top of the upper section is used as grasp. But as has been stated, the heat generated in the unit and escaping from within the same renders it almost impossible to even touch this insulated head, when the unit is 60 in operation. According to my invention, I substitute for the usual head-piece a head-piece 10 also of insulating material made in form of a cylindrical cup, the bottom 10' of which is provided centrally with an opening 65 10² to snugly fit over the extended upper end of the internal tube *a'* of the section *a'* of the heating unit projecting slightly into the cup as shown in Fig. 3. This cup-shaped head-piece is fixed in position to a ring *a''* 70 usually provided in the section *a'* by screws 11 and also has fixed on its bottom the terminals *c* for the electric leads *b*. Adapted to fit in the hollow of the head-piece 10, is a lid 12 of bakelite or other insulating material consisting of a ring-shaped portion 12' formed with a reduced annular neck 12² 75 projecting downwardly from the inner edge of the ring 12'. The inner diameter of this annular neck is about equal to the outer 80 diameter of the inner tube *a'* of the unit, while the outer diameter is smaller than the diameter of the hollow of the cup, so that, when the lid is positioned within the cup, there will be an annular groove 13 formed 85 through which are adapted to extend the inner parts of the leads *b* bearing flatly on the bottom of the cup. The outer diameter of the ring-shaped lid 12 is made equal to the diameter of the hollow of the cup, so that 90 said lid will snugly fit in the latter. When properly positioned and secured in the cup, the lower annular face of the lid is adapted to press tightly on the inner parts of the leads *b* and practically clamp them in position within the annular groove 13. Projecting vertically upwards from the upper 95 face of the annular lid, and constituting an integral part of said ring, is a beak-shaped guide member 12³, whose outer face is cylindrically curved and in linear extension of the outer periphery of the ring 12' and whose inner face is similarly curved and in extension of the inner periphery of the same. This beak is formed at its free end with a lateral projection 12⁴ serving as a grasp, and with a number of vertical perforations 12⁵ extending through the ring 12' and serving as passages for the leads *b*. The grasp 100 12⁴ is formed with a central opening 12⁶ 110

through which the surrounding air will circulate to cool the same. The upper and lower faces of the grasp may be roughened to prevent slipping of the fingers.

5 The lid is secured in position by a plurality of lateral screws 14 passed into it through the cup 10 as shown.

Owing to the construction described, the lead wires are securely held within the 10 groove 13 and prevented from becoming loose from the terminals and from causing a short circuit. The vertical beak or projection 12³ serves to guide the lead wires vertically down into the groove 13, so that there 15 will be no direct horizontal pull on the points of their attachment to the terminals. Furthermore the beak being made to extend sufficiently away from the top of the heated unit in conjunction with its air cooled grasp

20 affords convenient means for handling the unit without subjecting the operator to the heat radiating or escaping from the unit.

What I claim is:—

In an electric heating unit for permanent hair waving a cup shaped head piece of insulation material fixed to said unit and formed on its bottom with terminals for the electric leads, a lid of insulation material snugly fitting in said head piece and formed with a reduced annular neck, to form between itself and the wall of said cup an annular groove for the accommodation of said electric leads, said leads being adapted to be clamped by the lower face of said lid when tightened in position, a guide member integral with and projecting laterally and upwardly from said lid, said member being formed with perforations to serve as guide passages for said leads and with a ring shaped grasp projecting laterally from said 40 guide.

In testimony whereof I affix my signature.

WILLIAM SCHMITZ.
